UNITED STATES PATENT OFFICE.

JOHN C. BACKERT, OF NEW YORK, N. Y.

CUTTING-MACHINE.

1,137,251.

Specification of Letters Patent. Patented Apr. 27, 1915.

Application filed December 24, 1914. Serial No. 878,878.

To all whom it may concern:

Be it known that I, JOHN C. BACKERT, a citizen of the United States, residing at the city of New York, borough of Brooklyn, county of Kings, and State of New York, have invented certain new and useful Improvements in Cutting-Machines, of which the following is a full, clear, and exact description.

This invention relates to machines for cutting printers' rules, slugs, or other similar material, and aims to provide improved material gaging and holding means, in addition to other features.

A preferable embodiment of my improvement is described in detail in the following specification, taken in connection with the accompanying drawings, forming part thereof, and in which—

Figure 1 is a top plan view of an assembled cutting machine embodying the improvement of the present invention. Fig. 2 is an end elevation of the machine shown in Fig. 1, parts being broken away. Fig. 3 is a fragmentary top plan view of the cutting machine with the work back and gage positioned to give a cutting bevel to the material cut, this view illustrating the use of the filler angle gage block. Fig. 4 is an enlarged fragmentary section on the line 4—4 of Fig. 1. Figs. 5 and 6 are perspective detail views respectively of the work-clamp and filler-block.

Referring to these drawings by numerals, 1 indicates the base from which rises the standard 2 of a supporting frame, the bed-plate of which is indicated at 3, this plate being suitably grooved to receive the guiding tongues 4 of a sliding work-table 5 in the usual manner in machines of this class. This work-table 5 adjacent one end has an up-standing and overhanging arm 6 from which the upwardly extending arm 8 of a swinging back 9 is pivotally supported, as indicated at 7. This "back" provides a back-rest for work placed on the table and co-operates with a gage, as will be seen later. This back forms a hollow structure having parallel longitudinal sides connected by spanning bars, the bar at one end being continued and up-turned to form the hinging arm 8. One of these longitudinal bars, indicated at 9^a, forms the actual back against which the work rests and is preferably provided with a scale which has reference to a gage co-operating with the back. The back 9

may be held at various angles relative to the far edge of the table 5. To this end a pin 10 is suitably mounted in the frame on the back and co-operates with angle holes 11 formed in the table 5 to position the face of the back bar 9 at reverse angles relatively to the table and relatively to a cutting tool positioned adjacent this edge and parallel therewith. These angle holes 11 represent, in the present instance, reverse angles of 45° from the right angle or a 90° line, in which the back is held as shown in Fig. 1, in which position the pin 10 co-operates with a 90° hole 12 in the table (see Fig. 3).

The standard 2 of the machine frame is provided with journals 13, in which is mounted the shaft 14 of a cutting tool, a fly-wheel 15 and operating handle 16 being provided for this shaft. The cutting tool is in the form of a rotatable disk cutter 17 of suitable design and construction, the inner face of this disk lying in a plane closely adjacent to and parallel with the adjacent edge of the table 5. It will be evident that the table 5 may be moved by one hand of the operator toward the cutter while with the other hand the cutting disk is rotated through the crank-handle 16.

The gage which co-operates with the back 9 comprises a base 18 of channel formation fitting over and sliding longitudinally upon the bar 9^a of the back, this base carrying an indicator arranged to designate gage positions upon the scale on bar 9^a. The inner end of the base 18, or the end adjacent the cutter 17, is provided with a rigid right angular arm 19 having a slot therein intermediate its top and bottom edges and extending for a short distance from its forward end, this slot being designated at 20 in Fig. 2 and being for the purpose of permitting a clamping member to extend through and beyond the arm 19. The upper face of the arm 19 is provided preferably with a gage-plate corresponding with the gage-plate on the bar 9^a. The arm 19 extends at right angles to the adjacent face of the bar 9^a so that these bars form a right angle therebetween and will take and hold in proper position material of right angular configuration at one end. The arms 18 and 19 are connected by a web 22 having guide eyes 23 thereon to receive a filler angle block as hereinafter described. The gage itself is adjustable longitudinally of the back bar 9^a by means of a threaded block 24 engag-

ing the rotatable screw 25 mounted in the frame of the back and operated through a suitable hand wheel 26 to move the block 24 and the attached angle bars 18-19 longitudinally of the back, the scale and the bar 9^a thereof indicating the distance of the arm 19 from the cutting plane of the cutter 17. Preferably for quick adjustment I form the block 24 as a pivoted threaded segment normally spring-pressed into engagement with the adjusting screw 25. This segment may be pressed by hand out of engagement with the screw and the gage moved rapidly to any position desired; the fine adjustments being secured through the hand wheel 26.

The work may be clamped against the face of the back 9^a by means of a clamping bar 27 carried by the base 18 of the gage and movable therewith longitudinally of the back. This bar at its forward end and inner edge is provided with a relatively narrow clamping tooth 28. The rear portion of the bar extends through a slot in the guide 29 secured to the face of the base 18, being adjustably held in said guide with its forward end pressed against the work seated against the back by means of a friction spring 30 which not only serves to press the finger 28 but also serves to retain the bar 27 in any position to which it is moved longitudinally of the back. The outer edge of the bar 27 is formed with an operating finger 31, which likewise serves as a limiting stop for outward movement of the bar, and with a stop lug 32 which engages the guide 29 and prevents the bar being moved too far in the opposite direction so as to retract this forward end from within the slot 20 of the gage-arm 19. The finger 31 prevents the rear end of the clamping bar from being withdrawn from the adjusting guide. It will be understood, of course, that the friction of the spring 30 holds the clamping bar in longitudinally adjusted position and that the tension of the spring tends to move the forward clamping end of the bar into engagement with the work. By having the forward end 28 of the bar relatively narrow, it is possible to clamp very small pieces of material against the bar 9^a, this type of clamp being employed where the larger clamps are of too great breadth, as for instance in my prior Patent No. 1,114,329 of October 20, 1914.

I have heretofore stated that the back may be swung and held at various angles relative to the cutting plane and relative to the edge of the table 5 adjacent the cutter which table edge, in the present instance, is in parallel with the cutting plane. The back and gage may be swung to an angle of 45° and clamped there. Therefore a series of slugs 33 (Fig. 1) clamped by the bar 27 in the right angle formed by the bars 9^a and 19, will have their ends presented at an angle

of 45°. Frequently in constructing boxes, or any other work, it is desirable to trim the opposite ends at precisely reverse angles. With prior constructions the beveled ends of alined slugs could not engage the bar and at the same time rest against and in parallel with the back 9^a so as to present their untrimmed edges to the cutter at this reverse angle. I have provided an angle filler-block which may be moved into and out of position and with which the previously beveled ends of the trimmed slugs will coöperate instead of with the gage-bar 19. Such a filler-block is shown in the drawings, wherein a block 34 is provided having one edge 35 of a bevel corresponding to the bevel of cut, say 45°, and this bevel forming with an adjacent edge an angle of 45°. The block 34 is formed with an offset arm 36 having an attached shank 37 which slides and also swivels in the guide eyes 23 of the gage. The block 34 therefore may be swung in against the gage-bar 19, as shown in Fig. 3, and slugs 33 with their edges beveled to a reverse angle to the angle 33 of the block 90 may be held against the straight edge 38 of the block (which is parallel with the cutting plane) and against the bar 9^a which is inclined at the proper angle. They will therefore have their untrimmed ends presented at a reverse 45° angle to the cutter so that these ends may be trimmed at the reverse angle to the previously trimmed ends, the gage being adjusted upon the base to provide the requisite length. This block 34 is slotted intermediate its top and bottom as at 39 in Fig. 6 so that when it is used the forward clamping end of the bar 27 may be projected therethrough and may engage and hold the material, as indicated in Fig. 3 of the drawings. The filler-block 34 with its swiveling spindle 37 may be readily removed from the eyes 23 so that in the event the table is adapted to hold the back at a plurality of different angles, a plurality of such filler-blocks may be provided with their sides beveled to corresponding angles. The ends of the material may be beveled at the same angle and not reversed, if desired. This is accomplished by placing the previously beveled face (and not edge) against the angle filler-block.

While I have herein described a preferable embodiment of my improvement, I desire it understood that the same is susceptible of variation in structure and in relative arrangement of the parts within the spirit of the invention and the scope of the appended claims.

What I claim therefore and desire to secure by Letters Patent is:

1. In combination, a work table, a cutter positioned adjacent the edge thereof, said cutter and table being relatively movable, a back extending across said table in the direc-

tion of said cutter and transversely of the cutting plane, a work gage coöperating with and adjustable longitudinally relative to said back and extending transversely therefrom, and a clamping member arranged to engage and clamp material against said back at a point between said transverse gage and said cutter, said member extending longitudinally of said back and transversely of the cutting plane, and having a work engaging surface of narrow width whereby it may engage and clamp a narrow piece of material.

2. In combination, a work table, a cutter positioned adjacent the edge thereof, said cutter and table being relatively movable, a back extending across said table in the direction of said cutter and transversely of the cutting plane, a work gage coöperating with and adjustable longitudinally relative to said back and extending transversely therefrom, and an adjustable work clamping member adapted to extend substantially longitudinally of said back and beyond said transverse gage and in the direction of said cutter.

3. In combination, a work table, a cutter positioned adjacent the edge thereof, said cutter and table being relatively movable, a back extending across said table in the direction of said cutter and transversely of the cutting plane, a work gage coöperating with and adjustable longitudinally relative to said back and extending transversely therefrom, and an adjustable work clamping member adapted to extend substantially longitudinally of said back and beyond said transverse gage and in the direction of said cutter, said member having a work engaging portion of narrow width adapted to engage and clamp narrow material.

4. In combination, a work table, a cutter positioned adjacent the edge thereof, said cutter and table being relatively movable, a back extending across said table in the direction of said cutter, a work gage carried by and adjustable longitudinally of said back and extending transversely therefrom, and a work clamping member adjustable longitudinally relative to said back and arranged to extend through and beyond said transverse gage to engage and clamp material against said back at a point between said cutter and gage.

5. In combination, a work table, a cutter positioned adjacent the edge thereof, said cutter and table being relatively movable, a back extending across said table in the direction of said cutter, a work gage carried by and adjustable longitudinally of said back and extending transversely therefrom, and a work clamping member carried by and moving with said gage and itself adjustable longitudinally relative to said back and arranged to extend through and beyond

said transverse gage in the direction of said cutter.

6. In combination, a work table, a cutter positioned adjacent the edge thereof, said cutter and table being relatively movable, a back extending across said table in the direction of said cutter, a work gage carried by and adjustable longitudinally of said back and extending transversely therefrom, and a work clamping member carried by and moving with said gage and itself adjustable longitudinally relative to said back and arranged to extend through and beyond said transverse gage in the direction of said cutter, said member being provided at its end with a narrow work engaging and clamping tooth.

7. In combination, a work table, a cutter positioned adjacent the edge thereof, said table and cutter being relatively movable, a back extending across said table in the direction of said cutter, a work gage carried by and adjustable longitudinally of said back and having a gage arm extending at right angles from said back, said arm being slotted adjacent said back, a clamping bar carried by and movable longitudinally of said back and gage and arranged to project one end through said slot of said gage arm, with means for holding said bar in longitudinally adjusted position and with its projecting end in clamping engagement with work.

8. In combination, a work table, a cutter positioned adjacent the edge thereof, said table and cutter being relatively movable, a back extending across said table in the direction of said cutter, a work gage carried by and adjustable longitudinally of said back and having a gage arm extending at right angles from said back, said arm being slotted adjacent said back, a clamping bar carried by and movable longitudinally of said back and gage and arranged to project one end through said slot of said gage arm, with means for holding said bar in longitudinally adjusted position and with its projecting end in clamping engagement with work, said end having a narrow clamping tooth arranged to engage and hold narrow material against said back.

9. In combination, a work table, a cutter positioned adjacent the edge thereof, said table and cutter being relatively movable, a back extending across said table in the direction of said cutter and angularly adjustable relative to the aforesaid table edge, a gage carried by said back having a gage bar extending from said back at an angle thereto, an angle block movable into and out of engagement with said gage bar to present to material a gage face of an angularity different from that of said gage-bar, with means for clamping work against said back and said block gage face.

10. In combination, a work table, a cutter

4
positioned adjacent the edge thereof, said table and cutter being relatively movable, a back extending across said table in the direction of said cutter and angularly adjustable relative to the aforesaid table edge, a gage carried by said back having a gage bar extending from said back at an angle thereto, a slotted angle block movable into and out of engagement with said back and gage bar

10
at the apex of their angle to present to material a gage face of different angularity, and a clamping bar arranged to extend through said gage and block to engage and clamp work at a point beyond said block.

JOHN C. BACKERT.
